(57) **CLAIM**

The ornamental design for a surface pattern for textile products, as shown and described.

DESCRIPTION

FIG. 1 is a top plan view of a surface pattern for textile products showing my new design;

FIG. 2 is an enlarged detail view of a group of four surface pattern elements shown in FIG. 1; and,

FIG. 3 is an enlarged detail view of a single surface pattern element as shown in FIG. 1.

The broken lines define a portion of the textile products and indicate that the surface pattern continues indeterminately throughout the length and width of the textile products. The broken lines form no part of the claimed design.
